UNITED STATES PATENT OFFICE.

GEORGE BOHNER, OF CHICAGO, ILLINOIS.

IMPROVEMENT IN HANGING LAMPS.

Specification forming part of Letters Patent No. 126,254, dated April 30, 1872; reissue No. 5,534, dated August 19, 1873; application filed June 30, 1873.

To all whom it may concern:

Be it known that I, GEORGE BOHNER, of Chicago, in the county of Cook, State of Illinois, have invented an Improvement in Hanging Lamps, of which the following is a specification:

The nature of my invention relates to an improvement in hanging lamps, whereby the lamp can be raised and lowered at will; and it consists in the peculiar supporting-ring which embraces the upper part or flange of a shade or reflector, which ring is suspended from the ceiling by means of two chains passing over sheaves journaled in a horizontal bar, one end of each chain being attached to the ring and the other to the lamp; also, in suitable guides attached to the supporting-ring, whereby the shade or reflector is kept in a horizontal position.

Figure 1 is a sectional elevation of my invention. Fig. 2 is a sectional view of the supporting-ring. Fig. 3 is a plan of the same.

In the drawing, A represents a conical tin lamp-shade or reflector, having a vertical flange, *a*, turned at its upper or smaller end, which flange is embraced by the supporting-ring *B*, the same being made of any desirable material, and in such a manner that it can be sprung around the flange; or it may be formed in two sections hinged together, and provided with any suitable device for locking it around the said flange. C are guide-bars, curved inwardly from the ring so as to hang vertically on the inside of the flange *a*, and have secured to their inner faces eyes *c c*. D is a horizontal bar, in both ends of which are journaled

two sheaves, as at *b*. This bar is provided with a ring, *E*, by which the lamp can be suspended from a hook in the ceiling. F represents a lamp-socket, in which is placed a lamp, *G*. Extending upward from this socket are two rods, *H*, to the upper ends of which are attached the chains *I I*. From thence chains pass up through the eyes *c c* on the bars *C*, then over the sheaves at *b*, and thence down to the ring *B*, to which they are attached.

In order that the shade shall not be lowered too far down upon the lamp, I place suitable stops *d* in the rods *H*, which will allow the shade to descend until the said stops come in contact with the lower eyes *c c* on the guide-bars.

In place of the guide-bar and eyes, as described, tubes may be used for the same purpose, one of which is shown at *C'* in Fig. 1.

The weight of the ring and shade should counterbalance that of the lamp and socket.

What I claim as my invention, and desire to secure by Letters Patent, is—

1. The supporting-ring *B*, provided with the guide-bars *C* and guide-eyes *c c*, or tube *C'*, as and for the purpose set forth.
2. The shade *A*, ring *B*, guide-bar *C*, with their guide-eyes *c c* or equivalent, the bar *D*, sheaves *b*, socket *F*, lamp *G*, rods *H*, and chains *I*, when constructed, arranged, and operating as and for the purposes specified.

GEORGE BOHNER.
